UNITED STATES PATENT OFFICE.

ARTHUR BATES AND JOSEPH GOULBOURN, OF LEICESTER, ENGLAND, ASSIGNEES TO
UNITED SHOE MACHINERY CORPORATION, OF PATERSON, NEW JERSEY, A COR-
PORATION OF NEW JERSEY.

PRESS.

Application filed May 19, 1920. Serial No. 382,550.

To all whom it may concern:

Be it known that we, ARTHUR BATES and JOSEPH GOULBOURN, subjects of the King of England, residing at Leicester, Leicestershire, England, have invented certain Improvements in Presses, of which the following description, in connection with the accompanying drawings, is a specification, like reference characters on the drawings indicating like parts in the several figures.

This invention relates to machines for operating on sheet material and more particularly to presses of the class used in cutting sheet material by the employment of freely movable dies, a typical example of which is disclosed in United States Letters Patent No. 921,503, granted May 11, 1909, on application of Arthur Bates. It is to be understood, however, that the invention is applicable to classes of machines other than that illustrated in said patent.

Characteristically, machines of the type referred to in the foregoing statement have been provided with a single revolution clutch mechanism, thus eliminating the possibility of injury to the work or to the operator through an unexpected repetition of the pressure applying operation. However, in operating upon certain classes of materials notably tough or thick leathers or other fabrics, it is frequently necessary to employ a plurality of pressure applying operations, preferably in rapid succession, in order to secure clean cutting of the material.

In view of the above, it is an object of the invention to provide an improved press which will retain all the numerous advantages of the commercial form of machines as heretofore constructed and which will have increased usefulness and possibilities of greater speed in operation.

The invention comprises an improved machine which may operate, at the will of the operator, either once or a plurality of times as required by the character of the work, upon a single unsustained actuation of the starting mechanism.

In one aspect the invention comprises a machine wherein the starting means is so constructed and arranged that the extent of movement of a manually operable starting lever determines whether one or more

than one pressure applying operation is to take place.

In the illustrative machine, means is provided under the control of the operator for determining the extent of movement of the starting lever in accordance with the decision of the operator as to the number of pressure applying operations to be performed by the machine at a given time. Conveniently the means described comprises a plunger mounted in the handle of the starting lever and readily operable by a finger of the hand which grasps the handle.

In another aspect the invention comprises a machine wherein the clutch mechanism may be so operated as to provide for a plurality of pressure applying operations upon a single unsustained actuation of the starting means, and in which there is provision for preventing that operation of the brake which normally occurs at the end of one revolution of the shaft when a plurality of revolutions is to take place, means being preferably provided for applying the brake to the shaft at the end of a predetermined plurality of revolutions of the shaft.

From this viewpoint the invention comprises means for connecting a shaft with the source of power and means for preventing the application of the brake at the end of a single revolution of the shaft when the power has been connected for a predetermined plurality of revolutions of the shaft by a single unsustained actuation of the starting means. In the preferred construction means is provided under the control of the operator for preventing the application of the brake under certain conditions and there is provided also other means for automatically applying the brake at the time the power means is disconnected from the shaft at the end of a predetermined number of revolutions of the latter. Conveniently the clutch controlling means which would normally operate to disconnect the clutch at the end of a single revolution of the shaft is locked in inoperative position by means

under the control of the operator, and in order that the number of revolutions may be predetermined, means is provided for automatically withdrawing the locking means so that the clutch controlling means be-

comes operative to disconnect the clutch from the shaft at the proper time.

Other features of the construction and other combinations of parts will be described in the following detailed description and pointed out in the claims.

In the drawings:—

Figure 1 is a view in side elevation of one embodiment of the invention;

Fig. 2 is a side elevation partly in section of the clutch and brake mechanisms;

Fig. 3 gives two views of the handle on the starting lever, one in section and the other a side view taken from a position at right angles to that of the sectional view; and

Figs. 4, 5 and 6 are detail views of the clutch.

In the illustrative machine there is shown a work supporting bed 4 supported on the frame 6 of the machine and designed for co-operation with a presser member 8 carried by a post 10 for swinging movement over the bed so that the presser member may operate upon work in whatever position it may be placed upon the bed. It will be understood, therefore, that the post 10 is rotatably mounted in its bearings 12 and 14 so that the presser member 8 may be oscillated in the manner described. In addition, the post 10 is also mounted for reciprocation in its bearings so as to provide for moving the presser member toward and from work on the bed during pressure applying operations. For reciprocating the post, connections are provided between the main shaft 16 and the post comprising an eccentric strap 18 connected by a link 20 to a block 22 screw threaded into the lower end of the post, a ball bearing 24 being provided between the block 22 and a shoulder on the link 20 so that the post may be turned with a minimum of friction. Connected to the eccentric strap 18 by means of a pivot pin 26 is a rod 28, the lower end of which is in turn pivoted to a lever 30 mounted for rocking movement on the pivot 32 in the frame of the machine. The free arm of the lever is connected to operate a brake which, in the illustrative construction, is a brake band 34 surrounding a brake flange 36 fixedly attached to the shaft 16. It will be understood that as the post 10, together with the presser arm, moves upwardly the brake band is gradually applied by the operation of the lever 30 and that the brake band is fully applied to brake the shaft when the presser member arrives at its uppermost position of rest. The machine so far described is commonly known as the clicking machine and, if desired, reference may be had to the said patent for a more complete disclosure of the construction and mode of operation of an early type of the commercial clicking machine.

Whereas in the clicking machine as here-

tofore constructed a single actuation of the starting mechanism results in a single revolution of the main shaft accompanied by one pressure applying operation of the presser member which descends and then returns to its position of rest, the present invention provides means under the control of the operator for causing a single pressure applying operation or a predetermined plurality of pressure applying operations at the will of the operator upon a single actuation of the starting means. In the illustrative construction the clutch mechanism for connecting the power pulley 38 to the shaft 16 comprises a wedge member 40 (Figs. 2 and 5) pivoted on a stub shaft 42 and having a wedge or cam end portion 44 designed to control a bolt or plunger 46 in such a way that upon withdrawal of the wedge 44, the plunger 46 is actuated by a spring 47 (Fig. 5) to connect the power pulley to the shaft, the said wedge portion 44 operating to move the bolt or plunger 46 in the opposite direction normally at the end of a single revolution of the pulley, thus unclutching the pulley from the shaft. As shown, the plunger 46 is connected by an arm 49 to turn the screw 51 to effect an expansion or contraction of the ring 53 carried by the stationary clutch member 55, the ring upon expansion engaging the flange 57 of the loose pulley 38. For a more complete disclosure of the clutch mechanism, reference should be had to Patent No. 1,011,903, granted December 19, 1911 upon an application filed by Arthur Bates. As shown the wedge member 40 is operated to withdraw the cam or wedge portion 44 from operative position by means of a hand lever 146 (Fig. 1) mounted at 48 on the frame of the machine and connected to the wedge member 40 by means which provides for the release of the wedge member so that it may drop back into operative position to unclutch the power pulley at the end of a single revolution of the latter. These connections comprise a rod 50 pivoted at 52 to the rear end of the lever 146 and at its lower end to a link 54 which turns freely about a stub shaft 42 and carries a latch plate 56 normally engaged under another latch plate 58 at the upper end of a latch member 60 pivoted at 62 on the wedge member 40, a spring 64 being provided to hold the two latch plates 56 and 58 yieldingly in engagement with each other. The hand lever 146 is movable with the laterally swinging presser member 8, this construction being shown also in said Patent No. 921,503.

The operation of this part of the mechanism may be briefly described as follows:—Upon operating the starting lever 146 by depressing the handle 66 thereon, the link 54 is lifted and carries with it the latch 60 because of the engagement of the latch plate

56 underneath the latch plate 58, the lifting of the latch 60 operating to lift the wedge member 40 so that the cam or wedge portion 44 is withdrawn from contact with the bolt 46, thus permitting the clutching of the pulley 38 to the shaft. Very early in the revolution of the shaft the cam projection 68 on the clutch member 55 strikes the tail portion 70 of the latch 60 and causes the latch to move about its pivot 62 until the latch plate 58 is displaced and disengaged from the latch plate 56. When this takes place the wedge member 40 promptly drops back so that the wedge or cam portion 44 rests in a position to engage the bolt 46 and withdraw the same at the end of one revolution of the pulley.

In order that more than one revolution of the shaft may take place and, therefore, more than one pressure applying operation, there is provided means for locking the wedge member 40 in raised position so that it is not released at the end of one revolution. This means in the illustrative construction comprises a lock member 72 pivoted on a bearing 74 carried by the machine frame and having a projection 76 designed to engage the upper end of an arm 78 fixedly secured to the wedge member 40.

It will be clear that if the starting lever 146 is depressed far enough the link 54 will be carried up to such a distance that the arm 78 will be displaced to the left in Fig. 2 to a position which will permit the projection 76 to drop from the upper end of the arm and engage a side surface of the arm near the end thereof and thus lock the arm 78 and the wedge member 40 with the latter in inoperative position, even if the cam 68 should continue to contact with the tail portion 70 of the latch 60 it cannot cause release of the wedge member 40. Means is provided for unlocking the wedge member 40 at the end of a predetermined plurality of revolutions of the shaft, the construction in the present instance being such that the shaft is carried with the pulley throughout two revolutions of the shaft. Preferably the means for unlocking the wedge member 50 is automatic in its operation and comprises, in the illustrative construction a cam piece 80 mounted on the brake flange 36 and arranged to engage with a roller 82 at the lower end of the lock member 72, the arrangement being such that as the roller 82 rides up on the high part of the cam plate 80 the lock member 72 is raised to unlock the arm 78 to permit the wedge member 40 to drop back to operative position. Preferably a spring 84 is provided having one end attached to the lock member 72 and the other end of a stud 86 on the frame of the machine to hold the roller in position to be operated by the cam 80 and to actuate the lock member 72 promptly as the roller drops

off of the cam plate. It will be understood that the timing of the parts is such that the lock member 72 is actuated in the second revolution of the pulley and that it is not actuated effectively at the beginning of the first revolution because the handle of the starting lever 146 is held depressed an appreciable length of time during which the cam plate 80 passes beyond the roller 82 moving in the direction indicated by the arrow. It will be clear that the construction and arrangement of the described parts is such that one or a plurality of pressure applying operations will follow a single, unsustained operation of the starting lever. The illustrative machine differs in this respect from many well-known machines wherein the starting treadle must be held depressed to obtain a plurality of operations. In other words, in the machines to which reference is made, a sustained operation of the treadle is necessary to obtain a plurality of operations of the machine, the length of time that the treadle is held depressed corresponding directly to the number of cycles of the machine obtained.

As the brake mechanism is constructed in prior machines the brake is applied at the end of each revolution of the shaft. If, however, the shaft is to continue for a plurality of revolutions it is obvious that the brake should not be applied at the end of the first revolution. Means is, therefore, provided for preventing the application of the brake until the unclutching of the power pulley from the shaft. In the illustrative construction, this means for controlling the brake is under the control of the operator through the starting lever, though in another aspect it may be considered as automatically controlled from the mechanism which determines the clutching and unclutching of the power pulley with respect to the shaft. As shown, the brake band 84 is divided intermediate its ends at the point 88, a plate 90 being secured to one end of the brake band and a somewhat similar plate 92 to the other end of the brake band. One of these plates 92 carries a pivot 94 for a hook 93, the operative or hook end 98 being arranged to pass through an opening in the plate 90 and engage with its hook end in a recess and against a shoulder 100 on the plate 90. When thus engaged the hook operates to hold the two ends of the brake band fixedly together, it being clear, however, that if the hook be released from the recess and from contact with the shoulder 100, the brake band may be expanded so as to exert no pressure on the brake disk 36. Hence, means is provided for unhooking the two ends of the brake band toward the end of the first revolution of the pulley when the starting mechanism has been so actuated that a plurality of revolutions of the pulley and shaft

are to take place. As shown, the means for actuating the hook for the purpose set forth comprises two spring plates 102 which engage on opposite sides of the upper end of the hook 98 and are fixedly attached to a rocking sleeve 103 integral with member 40 and located on the stub shaft 42. The construction and arrangement are such that when the starting lever is depressed its full distance to permit the lock member 72 to operate and lock the wedge member 40 in inoperative position the plates 102 also operate to release the hook and thus free the ends of the brake band for movement relatively to each other. Hence, although the lever 30 is operated as usual, it fails to effect a braking action, movement of the brake lever under these conditions serving simply to separate the ends of the brake band. For the purpose of returning the ends of the brake band to engaging relation to each other and in such a position that the hook may again engage the recess and shoulder 100 in the plate 90 there is provided spring means tending always to keep the ends of the brake band together and to return them after any separation. While several different constructions of spring means may be used, that preferred comprises a bolt 104 threaded into plate 92 and extending loosely through an opening in plate 90 and upon which there is positioned a spring 106 confined between a surface on the plate 90 and a nut and washer 108 on the free end of the bolt 104. The tension of this spring can be so adjusted that it serves to return the ends of the brake band into contact with each other so that the hook 98 may engage as above described to lock the two ends of the brake band in such engagement that the band is to all intents and purposes a single brake member. When starting lever 146 is depressed only sufficiently to release the cam or wedge 44 and thus permit clutching of the power pulley to the shaft unaccompanied by operation of the lock member 72, the spring plates 102 do not move far enough to unhook the hook member 98 and hence the brake is operative at the end of a single revolution of the shaft. Should the hook member 98 be moved to unlatching position temporarily it immediately returns to operative position unless prevented as is the case when the wedge member 40 is locked in inoperative position, the spring fingers 102 being then held also in position to hold the latch out.

In order that the operator of the machine may be enabled to depress the starting lever 146 the desired distance to cause one revolution of the shaft and thus a single pressure applying operation or alternatively to cause a plurality of revolutions of the shaft and more than one operation of the presser member, there is provided means for controlling the movement of the handle 66 as to the ex-

tent of its movement whereby the operator is able to perform the operations above described with certainty and dispatch. In the illustrative construction, the means for controlling the movement of the handle 66 comprises a manually operable latch member 110 (Fig. 3) pivotally mounted at 112 in the upper end of the handle 66 and designed to engage the upper end of a guide rod 114, fixedly carried by the presser member 8, to limit the downward movement of the handle on the guide rod when only one revolution of the main shaft is desired. When a plurality of pressure applying operations is desired, the latch member 110 is arranged to pass into a recess 116 in the upper end of the guide 114 and thus offer no obstruction to the downward movement of the handle 66 on its guide rod 114. Hence if the operator wishes a plurality of pressure applying operations he grasps the handle 66 and depresses it as far as it will go. If but one pressure applying operation is desired he presses with his finger or thumb upon the end of a plunger 118 which is movable downwardly into the handle against the resistance of a light spring 120 which operates to return the plunger to its upper position of rest. Carried by the plunger 118 is a pin 122 arranged to pass through a slot 124 in the upper end of the latch member 110, the long axis of the slot being at an acute angle to the long axis of the latch member 110. Hence, if the plunger 118 be depressed the latch member 110 will be swung on its pivot 112 and its lower end will be engaged with the upper end of the guide 114, thus limiting the downward movement of the handle 66 on its guide rod 114. As shown the plunger 118 is provided with slots 126 on opposite sides which are open ended and permit the plunger 118 to move downwardly, although the pin 112 which supports the latch member 110 passes entirely across the chamber which receives the plunger.

The operation of the machine it is thought will be clear from the detailed description but may be briefly recapitulated as follows:—The operator places a piece of work on the supporting bed 4 and determines whether a single or a plurality of operations of the presser member is desired. If the former, the handle 66 is grasped and the plunger 118 depressed before depressing the handle. Under these conditions the starting lever is operated to such an extent that only one revolution of the shaft takes place and the presser member returns to its upper position of rest after a single operation of the work. On the other hand, if a plurality of pressure applying operations is desired, the handle 66 is grasped and depressed the full distance, the latch member 110 being inoperative as long as the plunger 118 is not actuated, and under these condi-

tions the starting lever is depressed to such an extent that the clutch controlling wedge member 40 is locked in inoperative position for more than one revolution of the pulley, 5 the shaft makes two revolutions and the presser member operates upon the work a corresponding number of times.

Having thus described the invention, what is claimed as new and desired to be 10 secured by Letters Patent of the United States is:—

1. In a machine of the class described, a shaft, a power pulley on the shaft, means for clutching the pulley to the shaft, control 15 mechanism operable upon a single unsustained actuation thereof for causing one or a plurality of revolutions of the shaft, a brake for the shaft, and means for controlling the operation of the brake so that it 20 will not be applied at the end of one revolution when the control mechanism has been so operated as to cause a plurality of revolutions of the shaft.

2. In a machine of the class described, a 25 shaft, a power pulley on the shaft, a clutch for connecting the pulley to the shaft, a brake band for stopping the shaft when the pulley has been unclutched therefrom, the brake band being divided to present end portions 30 adjacent each other, a latch operative to connect the end portions of the band, clutch controlling means, and connections between the clutch controlling means and said latch by which the latter is operated to unlatch or 35 release the ends of the brake band when the controlling means has been operated to clutch the pulley to the shaft for more than one revolution.

3. In a machine of the class described, a 40 shaft, a power pulley on the shaft, a clutch for connecting the pulley to the shaft for a single or for a plurality of revolutions, a brake band for operating on the shaft to stop the latter, the said brake band having 45 end portions yieldingly connected together so that the brake band can expand instead of acting as a brake, a latch normally operative to hold the ends of the brake band together, clutch operating means under the control of the operator, and connections between the clutch operating means and the latch for unlatching and thus releasing the ends of the brake so that when the clutch 50 operating means is actuated to cause a plurality of revolutions the brake is not applied at the end of a single revolution but becomes operative only when the pulley is unclutched from the shaft.

4. In a machine of the class described, a 55 shaft, a power pulley on the shaft, a clutch for connecting the power pulley to the shaft, means for controlling the clutch comprising a wedge or cam member, means comprising a lever under the control of the operator for lifting the wedge member so that the clutch

is thrown into operation, means for locking the wedge member in inoperative position for a plurality of revolutions of the power pulley, braking means normally operative to brake the shaft at the end of a single revolution, and connections between the locking means and the braking means for preventing effective application of the latter until the pulley is unclutched from the shaft.

5. In a machine of the class described, a 75 shaft, a power pulley loosely mounted on the shaft, a clutch for connecting the pulley to the shaft, means under the control of the operator for controlling the clutch comprising a wedge member which when operated is followed by a clutching of the pulley to the shaft, a member for locking the wedge member in inoperative position for a plurality of revolutions of the power pulley, automatic 80 means for unlocking or releasing the locking member, a latch, a braking means comprising a brake band having ends connected by said latch, and connections between the latch and the locking member so constructed and arranged that when the lock moves to operative position the latch is released thus preventing effective application of the braking means until the pulley is unclutched from the shaft at the end of the plurality of revolutions of the latter.

6. In a machine of the class described, a 90 shaft, a power pulley loosely mounted on the shaft, a clutch for connecting the pulley to the shaft, means under the control of the operator for controlling the clutch comprising a wedge member which when manually operated is followed by clutching of the power pulley to the shaft, a member for locking the wedge member in inoperative position so that the clutch remains operative to connect the pulley to the shaft during a plurality of revolutions of the pulley, and means for automatically releasing the wedge member so as to unclutch the pulley at the 95 end of the predetermined number of revolutions.

7. In a machine of the class described, a 105 shaft, a power pulley on the shaft, a clutch for connecting the pulley to the shaft, a brake for stopping the shaft when the pulley is unclutched, means comprising a lever normally operable at each revolution of the shaft to cause the application of the brake, means under the control of the operator for operating the clutch, and connections between the last mentioned means and the brake for preventing the operation of the 115 brake if more than one revolution of the shaft is to occur.

8. In a machine of the class described, a 125 shaft, a power pulley loosely mounted on the shaft, a clutch for connecting the pulley to the shaft, a starting lever for controlling the clutch so arranged that the extent of movement of the starting lever determines 130

whether one or more than one revolution of the shaft is to take place, a braking means for stopping the shaft when the pulley is unclutched from the shaft, a lever for operating the braking means normally at the end of each revolution of the shaft, and means under the control of the operator for preventing the application of the braking means at the end of a single revolution when the starting lever has been operated in such manner as to cause a plurality of revolutions of the shaft.

9. In a machine of the class described, a work supporting bed, a presser member movable toward and from the bed in pressure applying operations, power means for moving the presser member in the manner described, manually controllable means for causing at the will of the operator one or 20 more than one pressure applying operation of the presser member upon a single unsustained operation of the manually controllable means, braking means for operating on the power means normally at the end of each cycle of operations, and means for controlling the braking means so that it is not applied at the end of the first cycle when the machine is to continue through a second cycle of operations.

10. In a machine of the class described, a work supporting bed, a presser member, power means comprising a shaft for moving the presser member toward and from the bed in pressure applying operations, a power pulley rotatable on the shaft, means associated with the shaft and the pulley and under the control of the operator for connecting the shaft to the power pulley for one or more pressure applying operations, 40 a braking means normally operative to brake the shaft at the end of a single revolution of the latter, and means automatically operative to prevent the action of the braking means at the end of one revolution when the machine is to continue through two revolutions of the shaft.

11. In a machine of the class described, a work supporting bed, a presser member, power means comprising a shaft for moving the presser member toward and from the work supporting bed in pressure applying operations, a power pulley on the shaft, means under the control of the operator for connecting the pulley to the shaft, a braking means normally operative to stop the rotation of the shaft at the end of a single revolution of the latter, and means associated with the means for connecting the pulley to the shaft for controlling the operation of said braking means so that the latter will not be operative until the end of the second revolution of the shaft when two pressure applying operations of the presser member are to take place at the will of the operator.

12. In a machine of the class described, a work supporting bed, a presser member, power means for moving the presser member toward and from the work supporting bed, manually operable means for controlling said power means and movable to initiate one or a plurality of pressure applying operations, and means under the control of the operator for determining the extent of movement of the manually operable means so that the number of pressure applying operations of the pressure member may be predetermined at the will of the operator.

13. In a machine of the class described, a work supporting bed, a presser member, power means for moving the presser member toward and from the work supporting bed, manually operable means comprising a lever for controlling said power means and movable to initiate one or a plurality of pressure applying operations, and means under the control of the operator for determining the extent of movement of the lever so that the number of pressure applying operations of the presser member may be predetermined at the will of the operator.

14. In a machine of the class described, a work supporting bed, a presser member, power means for moving the presser member toward and from the work supporting bed, manually operable means for controlling said power means comprising a lever, a handle associated with the lever, and means in the handle comprising a stop for limiting the movement of the handle when only one pressure applying operation of the presser member is desired.

15. In a machine of the class described, a work supporting bed, a presser member, power means for moving the presser member toward and from the work supporting bed, manually operable means for controlling said power means comprising a lever, a handle associated with the lever and movable to an extent to cause a plurality of pressure applying operations of the presser member, means in the handle and under the control of the operator for locking the handle against such movement as will cause a plurality of operations, and means for returning the locking means to inoperative position.

16. In a machine of the class described, a shaft, a power pulley on the shaft, a clutch for connecting the pulley to the shaft, a brake band for stopping the shaft when the pulley has been unclutched therefrom, the ends of the brake band being connected by a latch, clutch controlling means, and connections between the clutch controlling means and said latch by which the latter is operated to unlatch or release the ends of the brake band when the clutch controlling means has been operated to cause more than one revolution of the shaft.

17. In a machine of the class described, a work supporting bed, a presser member, power means for moving the presser member toward and from the work supporting bed, manually operable means for controlling said power means comprising a lever, a handle associated with the lever and movable to cause a plurality of pressure applying operations of the presser member, and means movable in the same direction as the handle for locking the handle against such movement as will effect a plurality of operations of the presser member and at the same time permitting the handle to move a distance sufficient to initiate a single pressure applying operation.
18. In a machine of the class described, a work supporting bed, a presser member, power means for moving the presser member toward and from the bed in pressure applying operations, starting means for controlling said power means, a handle associated with said starting means, the handle being movable to initiate normally a plurality of operations of the presser member, and means under the control of the operator for limiting the movement of the handle so as to prevent such movement of the handle as will initiate a plurality of operations of the presser member.
19. In a machine of the class described, a work supporting bed, a presser member, power means for moving the presser member toward and from the work supporting bed, manually operable means for controlling said power means comprising a lever operative to initiate one or a plurality of pressure applying operations, and means under the control of the operator for limiting the movement of the lever when only one pressure applying operation of the presser member is desired.
20. In a machine of the class described, a work supporting bed, a presser member, power means for moving the presser member toward and from the work supporting bed, manually operable means for controlling said power means comprising a lever operative to initiate one or a plurality of pressure applying operations, a handle associated with the lever, and means in the handle for limiting the movement thereof when it is desired to effect only one pressure applying operation of the presser member.
21. In a machine of the class described, a work supporting bed, a presser member, power means for moving the presser member toward and from the work supporting bed, manually operable means for controlling said power means comprising a lever, a handle associated with the lever and movable to cause a plurality of pressure applying operations of the presser member, and means movable in the same direction as the handle for locking the handle and lever against such movement as will effect a plurality of operations of the presser member and at the same time permitting the handle to move a distance sufficient to initiate a single pressure applying operation.
22. In a machine of the class described, a work supporting bed, a presser member, power means for moving the presser member toward and from the bed in pressure applying operations, starting means for controlling said power means, a handle associated with said starting means, a guide on which the handle is movable to initiate normally a plurality of operations of the presser member, and means under the control of the operator for limiting the movement of the handle on the guide so as to prevent such movement of the handle as will initiate a plurality of operations of the presser member.
23. In a machine of the class described, a work supporting bed, a presser member, power means including a shaft for moving the presser member toward and from the bed in pressure applying operations, starting means comprising a lever for controlling said power means, a handle associated with said starting means, a guide on which the handle is movable, and a finger piece movable in the same direction as the handle for limiting the movement of the handle.
24. In a machine of the class described, a work supporting bed, a presser member, power means including a shaft for moving the presser member toward and from the bed in pressure applying operations, starting means comprising a lever for controlling said power means, a handle associated with said starting means, a guide on which the handle is movable and a finger piece movable in the same direction as the handle for controlling the movement of the handle.
25. In a machine of the class described, a work supporting bed, a presser member, power means including a shaft for moving the presser member toward and from the bed in pressure applying operations, starting means comprising a lever for controlling said power means, a handle associated with said starting means, a guide on which the handle is movable, and means in the handle and under the control of the operator for locking the handle against movement on the guide.
26. In a machine of the class described, a work supporting bed, a presser member, power means including a shaft for moving the presser member toward and from the bed in pressure applying operations, starting means comprising a lever for controlling said power means, a handle associated with said starting means, a guide on which the handle is movable, and means comprising

ing a member slidable in the direction of movement of the handle for contacting with the end of the guide and thus preventing further movement of the handle on the 5 guide.

27. In a machine of the class described, a work supporting bed, a presser member, power means including a shaft for moving the presser member toward and from the 10 bed in pressure applying operations, starting means comprising a lever for controlling said power means, a handle associated with said starting means, a guide on which the handle is movable, and a member slid- 15 able in the end of the handle so as to be operable by a finger of the hand which grasps the handle for locking the handle to the guide.

28. In a machine of the class described, 20 a work supporting bed, a presser member, power means including a shaft for moving the presser member toward and from the bed in pressure applying operations, starting means comprising a lever for controlling 25 said power means, a handle associated with said starting means, a guide on which the handle is movable, and a member movable into the end of the handle by a finger of the hand which grasps the handle for 30 locking the handle against movement on the guide.

29. In a machine of the class described, a work supporting bed, a presser member, power means including a shaft for moving 35 the presser member toward and from the bed in pressure applying operations, starting means comprising a lever for controlling said power means, a handle associated with said starting means, a guide mounted 40 on the presser member and on which the handle is movable, and a member movable into the handle by a finger of the hand which grasps the handle and comprising a latch which is operated by the movement 45 of the member to lock the handle on the guide.

30. In a machine of the class described, a work supporting bed, a presser member movable over the bed, power means comprising 50 a shaft for moving the presser member toward and from the bed in pressure applying operations, a power pulley on the shaft, means under the control of the operator for clutching the pulley to the shaft, a braking 55 means independent of the clutching means and normally operable to stop the shaft after a single revolution, a control member, and means operable upon a single unsustained actuation of the control member for 60 preventing the operation of the braking means at the end of a single revolution of the shaft when it is desired that the machine continue in a plurality of cycles of operation.

65 31. In a machine of the class described,

a work supporting bed, a presser member movable over the bed, power means comprising a shaft for moving the presser member toward and from the bed in pressure applying operations, a power pulley 70 on the shaft, means for controlling the connection of the pulley to the shaft for one or for a predetermined plurality of revolutions of the power pulley, braking means operable to brake the shaft at the end of a 75 single revolution thereof, and means for preventing the application of the braking means at the end of a single revolution of the shaft when said controlling means has been operated to initiate said predetermined 80 plurality of revolutions of the shaft.

32. In a machine of the class described, a work supporting bed, a presser member movable over the bed, power means comprising a shaft for moving the presser 85 member toward and from the bed in pressure applying operations, a power pulley on the shaft, means under the control of the operator to connect the power pulley to the shaft for a predetermined plurality 90 of revolutions of the power pulley, a braking means normally operative for braking the shaft at the end of a single revolution thereof, means under the control of the operator for preventing such normal operation 95 of the braking means, and means for automatically causing the operation of the braking means at the end of said predetermined number of revolutions of the shaft.

33. In a machine of the class described, a work supporting bed, a presser member movable laterally over the bed and also toward and from the bed, power means comprising a shaft for causing movement of the presser member toward and from the 100 bed in pressure applying operations, a power pulley on the shaft, a braking means normally operative to brake the shaft at the end of a single revolution thereof, and a single means for causing the clutching of 105 the power pulley to the shaft and for controlling the action of said braking means, said last-mentioned means comprising a manually operable lever movable with the presser member in lateral directions over 110 the bed.

34. In a machine of the class described, a shaft, a power pulley on the shaft, a clutch for connecting the power pulley to the shaft, means for controlling the clutch comprising 115 a cam member, means comprising a lever under the control of the operator for lifting the cam member so that the clutch is thrown into operation, means normally operative to release the cam member to effect a single 120 revolution of the shaft, and means for locking the cam member in inoperative position for effecting a plurality of revolutions of the power pulley.

35. In a machine of the class described, a 125

130

shaft, a power pulley loosely mounted on the shaft, a clutch for connecting the pulley to the shaft, means under the control of the operator for controlling the clutch comprising a wedge member which when operated is followed by a clutching of the pulley to the shaft, a member for locking the wedge member in inoperative position for effecting a plurality of revolutions of the power pulley, and automatic means for unlocking or releasing the locking member.

36. In a machine of the class described, a shaft, a power pulley loosely mounted on the shaft, a clutch for connecting the pulley to the shaft, a lever manually operable for controlling the clutch comprising a wedge member which when operated is followed by clutching of the power pulley to the shaft, and a member controlled by said lever for locking the wedge member in inoperative position so that the clutch remains operative to connect the pulley to the shaft during a plurality of revolutions of the pulley.

37. In a machine of the class described, a work supporting bed, a presser member, power means including a shaft for moving the presser member toward and from the bed in pressure applying operations, starting means for controlling said power means and operable through predetermined distances selectively determinable by the operator for causing one or more than one operation of the presser member, and means, arranged to be manipulated by the operator, for setting limits to the movements of the starting means.

38. In a machine of the class described, a work supporting bed, a presser member, power means including a shaft for moving the presser member toward and from the bed in pressure applying operations, starting means comprising a lever movable through predetermined distances for controlling said power means, and means under the control of the operator for determining selectively the limits of movement of the

starting lever whereby one or more than one operation of the presser member takes place.

39. In a machine of the class described, a work supporting bed, a presser member, power means comprising a shaft for moving the presser member toward and from the work supporting bed in pressure applying operations, a clutch on the shaft for connecting the latter to the source of power, manually operable means comprising a lever for initiating operation of the machine and for selectively determining the number of pressure applying operations upon a single unsustained actuation of the manually operable means, and means for controlling the lever and thus assisting the operator in selectively determining the number of pressure applying operations.

40. In a machine of the class described, a shaft, a circular member fixedly secured to the shaft, a brake band arranged to embrace the circular member, the said brake band being divided and provided intermediate of its ends with a latch for releasably connecting the divided portions, and manually operable means for controlling the latch.

41. In a machine of the class described, a shaft, a brake for the shaft, power means for operating the brake, means under the control of the operator for rendering the brake inoperative, and automatic means for restoring the brake to operative condition.

42. In a machine of the class described, a shaft, a brake for the shaft, power means for applying and releasing the brake in normal operations of the machine, and manually operated means for rendering the brake inoperative by said power means.

In testimony whereof we have signed our names to this specification.

ARTHUR BATES.
JOSEPH GOULDBOURN.
